UNITED STATES PATENT OFFICE.

HUGO RICHTER, OF DRESDEN, GERMANY.

BRIDLE-BIT.

SPECIFICATION forming part of Letters Patent No. 664,970, dated January 1, 1901.

Application filed August 21, 1899. Serial No. 728,022. (No model.)

To all whom it may concern:

Be it known that I, HUGO RICHTER, a subject of the King of Saxony, and a resident of Wachwitzhöhe, b. Dresden, in the Kingdom 5 of Saxony, German Empire, have invented certain new and useful Improvements in Bits particularly for Use in Breaking or Training Colts and Horses, of which the following is a specification.

10 My invention relates to a new and improved bit particularly for use in breaking or training colts and horses and is so constructed that the pressure of the bridle-reins upon the bit does not act upon the mouth of the animal, thus hardening the same, but acts directly upon the inner portion of the mouth—that is, against the roof and tongue—thus 15 teaching the horse the meaning of the different pressures and avoiding all danger of making the latter "hard-mouthed."

In the accompanying drawings, which form an inseparable part of this specification, and in which similar letters refer throughout to similar parts, Figure 1 is a plan view of my 25 invention. Fig. 2 shows the bit opened.

I employ a shell A, formed of two similarly-constructed sections secured together in any desired manner and having in each end a longitudinally-extending rod or plunger d. Fas- 30 tened to each end of said shell is a fulcrum b, upon which is mounted an arm B, to the other end of which the bridle-reins are adapted to be fastened. Each of these arms B is piv- 35 otally connected by a pin c to the outer end of the respective adjacent rods d, which latter are held in a normal outward position through the action of springs h h, mounted within said shell. The inner end of each of said plun- 40 g-rod d has an oval-shaped plate or ear d' formed thereon and adapted to engage with lugs e e, projecting therein from levers g g, which levers are pivotally mounted upon pins f f on the shell A, as shown.

The operation of the bit will be clearly un- 45 derstood from the foregoing description and accompanying drawings when taken in connection with the following statement.

Placing the bit in the horse's mouth with bridle-reins secured to arms B B, it is desired 50 to guide the animal to the right. By prop- erly pulling the rein the arm B is swung upon

its fulcrum b, whence the rod d is pressed inwardly, compressing the spring h, and the plate d' strikes the two lugs e, (see Fig. 2,) each projecting from the two arms g into the oval-shaped hole of said plate d', whence the arms g are revolved about their axle-pins f f and, emerging from the shell, press, respectively, against the roof and bottom of the mouth, thus teaching the animal the significance of the pressure without hardening the mouth. Upon releasing the rein the spring h forces the rod d out, which latter in turn draws the said levers within the shell.

Having now particularly described and as- 65 certained my said invention and in what manner the same is to be used, I declare that what I claim is—

1. In a new and improved training-bit the combination of a shell, plungers therein, le- 70 vers on the inner ends of said plungers and means for operating said plungers, substan- tially as described.

2. In a new and improved bit, the combi- 75 nation of a shell, plungers mounted longitudinally therein, ears on the inner ends of said plungers, levers pivoted on pins, lugs on said levers engaging with an oval slot in said ears, a spring in connection with each of said plungers and arms on the outer ends of said shells, 80 said arms being pivotally connected with said plungers, substantially as described.

3. In a new and improved training-bit, the combination of a shell, a fulcrum on each end thereof, an arm mounted on each fulcrum, a 85 plunger in each end of said shell and each plunger being pivotally connected to its ad- jacent arm, a spring at each end of said shell and adapted to hold said plungers normally in an outer position, ears on the inner ends 90 of said plungers, each ear having an oval slot, levers pivotally mounted within said shell, lugs upon said levers and within said slots, the latter receiving the lugs for the purpose of operating said levers, substantially as de- 95 scribed.

Dated this 5th day of August, 1899.

HUGO RICHTER.
